UNITED STATES PATENT OFFICE.

JAMES WILLIAM DECKERT, OF MORRISTOWN, TENNESSEE.

SECTIONAL-RING FRICTIONAL ROLLER FOR LEATHER-SPLITTING MACHINES.

SPECIFICATION forming part of Letters Patent No. 777,248, dated December 13, 1904.

Application filed May 23, 1904. Serial No. 208,306. (No model.)

To all whom it may concern:

Be it known that I, JAMES WILLIAM DECKERT, a citizen of the United States, residing at Morristown, in the county of Hamblen and State of Tennessee, have invented certain new and useful Improvements in Sectional-Ring Frictional Rollers for Leather-Splitting Machines; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in sectional-ring friction-rolls for use on band or belt knife leather-splitting machines; and the object of the invention is to produce an apparatus whereby more perfect and finished split leather may be produced than by the machines commonly employed.

More specifically, the invention comprises a friction-roll made up of sections mounted upon a flexible cable having ball-and-socket connections with suitable anchorage members and so arranged that as the hide passes between the gage-roll and the sectional roller and against the splitting-knife the sections of the friction-roller will be adapted to bear against a rubber cylinder and by two or more of the sections yielding together to produce an undulating surface to the leather when uneven portions thereof come in contact with the sections of the roller without presenting sharp corners to the leather, as is commonly a fault with sectional friction-rollers now in use upon machines of this character.

My invention consists, further, in various details of construction and in combinations and arrangements of parts, which will be herein-after fully described and then specifically defined in the appended claims.

My invention is illustrated in the accompanying drawings, in which—

Figure 1 is a front elevation of a portion of a leather-splitting machine, showing the relative positions of the sectional roller, the gage, and rubber roller. Fig. 2 is an enlarged longitudinal central sectional view through

my improved sectional roller, showing the cable in elevation. Fig. 3 is a sectional detail view of one of the sections of the sectional roller. Fig. 4 is a diagrammatic view showing the undulating surface that is afforded by the flexible cable upon which the sections of my friction-roller are mounted, and Fig. 5 is a similar view showing the abrupt surfaces that are presented to the hide in the machines now commonly employed.

Reference now being had to the details of the drawings by letter, A indicates the frame of an endless-belt leather-splitting machine having the general features of the usual machines of this character, provided with a supporting-roller B, suitably journaled in the frame and upon which the cushion-roller C rests.

D designates a gage-roller, and E designates a block having a socket E' in one face thereof, and said block is fastened to the frame by means of bolts F. Each of said blocks E, there being one upon each opposite side of the frame and of similar construction, has an aperture e leading through the same, the walls of said apertures being tapered, as shown in the detail sectional view of the drawings, and each socket member E is adapted to receive an end of a flexible wire cable H, each end of said cable having a ball K either integral therewith or secured to the ends of said cable, and said balls are adapted to have bearing in the recessed socket portions of said plates, as shown in the detail view of the drawings, and the tapering walls of the apertures e are for the purpose of allowing the cable to yield in different directions, as will be understood.

Mounted upon said cable is a series of sectional rings N, which to all outside appearance are similar to the usual sectional rings employed upon rigid rods or shafts; but each of said sections N upon reference to the sectional view of the drawings will be seen is provided with a concaved recess N' in one end, while the opposite end is convexed, as at O, adapted to conform to the concaved recess of the adjacent end of a section in which it is adapted to nest, as shown in the sectional view of the drawings. Each of said sections is apertured, the walls of which are provided with

threads Q for the purpose of fitting upon the spindle when it is desired to true the same when the various sections become irregular from wear. After the sections are placed 5 upon the cable in the manner shown and described they are held interlocked by means of the collars R, one being held in contact with each end of the series of sections and fastened to the cable by means of a set-screw R'.

- 10 By the provision of a roller embodying the features of my invention it will be observed that when hides are passed between the sectional and gage rollers and when uneven portions of the hide contact with one or another 15 of the sections of the roller one or more of said sections will yield slightly, forming an undulating surface which will not leave marks upon the hide, as is commonly the case where but one of the sections yields independent of 20 the others, thus leaving a sharp corner or shoulder which has a tendency to leave an impression upon the hide. In the drawings I have shown a diagrammatic view illustrating the undulating surface side by side with the 25 surface that is afforded by offsets or shoulders in the machines commonly in use. As the pressure is removed from the undulating surface caused by uneven surfaces of hides passing between the sectional frictional roller 30 and the gage the elasticity of the cable will serve to return the sections to their normal positions.

While I have shown a particular detailed construction of apparatus illustrating the features of my invention, it will be understood 35 that I may vary the same, if desired, as to certain differentiations without in any way departing from the spirit of the invention.

Having thus fully described my invention, 40 what I claim as new, and desire to secure by Letters Patent, is—

1. In combination with a leather-splitting machine having the usual gage-rollers, cut-

ting-knife and yielding cylinder, a flexible cable having ball-and-socket joints at its ends 45 and positioned intermediate said cylinder and knife, a series of interlocking cylindrical sections mounted upon said cable and adapted to present an unbroken undulating surface to a hide passing between said sections and gage- 50 roller, as set forth.

2. In combination with a leather-splitting machine having the usual gage-roller, cutting-knife and yielding cylinder, a flexible cable positioned intermediate said cylinder and 55 knife, the ends of which cable are formed with balls, apertured socket members through which said cable passes and in which said balls have bearings, the apertures in said socket members being tapered, a friction-roll made 60 up of a series of sections interlocking with one another, and means for holding said sections interlocked, whereby as uneven portions of hides are passed between the friction and gage rollers, an unbroken, undulating surface 65 is presented upon the friction-roller, as set forth.

3. In combination in a leather-splitting machine, the gage-roller, yielding cylinder and cutting-knife, socket members secured to the 70 frame of the machine, a flexible cable intermediate said cylinder and knife and having sockets in which the balls at the ends of said cable have bearings, a friction-roller made up of apertured sections strung upon said cable, 75 one end of each section being concaved and the opposite end convexed, collars adapted to hold said sections interlocked, and set-screws carried by said collars and adapted to hold the latter against said cable, as set forth.

In testimony whereof I hereunto affix my signature in presence of two witnesses.

JAMES WILLIAM DECKERT.
